(57) **CLAIM**

The ornamental design for a clamp ring for UV generator, as shown and described.

DESCRIPTION

FIG. 1 is an isometric view of a clamp ring for UV generator thereof;

FIG. 2 is a side plan view of the clamp ring for UV generator thereof;

FIG. 3 is a top plan view of the clamp ring for UV generator thereof; and,

FIG. 4 is a bottom plan view of the clamp ring for UV generator thereof.

Any broken lines shown in the figures are for the purpose of illustrating portions of the clamp ring for UV generator which form no part of the claimed design.

No claim is made regarding the position or relative size of the design with respect to the clamp ring for UV generator.
